UNITED STATES PATENT OFFICE.

FREDERICK ENGELHARDT, OF ST. JOHNSVILLE, NEW YORK.

PIANISSIMO DEVICE FOR PIANO-ACTIONS.

SPECIFICATION forming part of Letters Patent No. 770,568, dated September 20, 1904.

Application filed July 22, 1904. Serial No. 217,614. (No model.)

To all whom it may concern:

Be it known that I, FREDERICK ENGELHARDT, a citizen of the United States, residing at St. Johnsville, Montgomery county, State of New York, have invented new and useful Improvements in Pianissimo Devices for Piano-Actions, of which the following is a specification.

This invention relates to a pianissimo device for piano-actions which is simple of construction, is readily accessible, and permits of ready adjustment.

In the accompanying drawings, Figure 1 is a side view of an upright-piano action embodying my invention and showing the parts in their normal position; Fig. 2, a side view of the lower portion of the action, showing the position of the parts when the soft pedal is depressed; Fig. 3, a detail of the frame for supporting the hanger; Fig. 4, a front view of the elbow-lever. Figs. 5 and 6 are details of the transverse rod, and Fig. 7 a detail of a modification of the finger pivoted to the elbow-lever.

The letter *a* represents the key of a piano-action, and *b* is the capstan. To a flange *c* of action-rail *c* is fulcrumed at *d* an elbow-lever *d*, having a forwardly-extending cushioned foot *d*. This foot rests upon the capstan *b* and is adapted to support the lower end of the abstract *e*, the upper end of which is pivoted at *f* to the wippen *f*. At its angle the elbow-lever *d* is grooved, as at *d*, to receive the rear end of a finger *g*, pivoted to the lever *d* at *g*. The finger *g* is by pivot *g* also connected to the abstract *e* and rests with its front cushioned end upon a transverse rod *h*. This rod is operatively connected to the hammer-rail *i* in such a manner as to rise and fall therewith, and to thus swing the finger *g* upon its fulcrum *g*. As shown, the rod *h* is perforated transversely and mounted adjustably upon a pair of arms *j*, fulcrumed to action-frame *A* at *j*. Set-screws *j*, Fig. 5, permit the rod *h* to be clamped to arms *j* after being adjusted. Through an upright perforation of rod *h* extends a hanger *k*, suspended at its

upper headed end from a bent perforated frame *l*. This frame is provided with a slot *l*, engaged by a set-screw *m* for connecting the frame adjustably to the hammer-rail *i*. In this way the frame *l*, together with the upper end of hanger *k*, may be adjusted backward and forward. The lower end of hanger *k* is threaded and carries a nut *n*, which supports a coniform leather washer *n*, countersunk into lower side of rod *h*, Fig. 6. By manipulating the nut *n* the elevation of the rod *h* may be readily adjusted.

The operation will be readily understood. Normally the capstan *b* transmits the motion of the key through lever-foot *d* directly to abstract *e* and thence to the wippen *f*, Fig. 1. When the soft pedal (not shown) is depressed, it will by lifter *o* raise hammer-rail *i*, and the latter will by frame *l* and hanger *k* correspondingly elevate rod *h*. The rod *h* will raise the forward end of finger *g* to lift abstract *e* off lever-foot *d* and correspondingly increase the reach of the action. Motion will now be transmitted from capstan *b*, through lever *d*, fulcrum *g*, finger *g*, pivot *g*, and abstract *e*, to the wippen.

In Fig. 7 the finger *g* does not rest directly upon the transverse rod *h*, but is provided with a cushioned set-screw *p*, that engages the rod. By this construction the reach of every single key may be separately adjusted.

What I claim is—

1. A pianissimo device for piano-actions composed of a key, a capstan, an elbow-lever having a foot that is supported upon the capstan, and a finger pivoted to the elbow-lever and operatively connected to the action, substantially as specified.

2. A pianissimo device for piano-actions composed of a key, a capstan, an elbow-lever having a foot that is supported upon the capstan, a finger pivoted to the elbow-lever, an abstract pivoted to the finger, and means for operating the finger, substantially as specified.

3. A pianissimo device for piano-actions composed of a key, a capstan, an elbow-lever

having a foot that is supported upon the capstan, a finger pivoted to the elbow-lever, an abstract pivoted to the finger, a transverse rod engaging the finger, a hammer-rail, and a hanger which is adjustably secured to the hammer-rail and to the transverse rod, substantially as specified.

Signed by me at New York city, (Manhattan,) New York, this 21st day of July, 1904.

FREDERICK ENGELHARDT.
